UNITED STATES PATENT OFFICE.

WILLIAM T. MERSEREAU, OF ORANGE, NEW JERSEY.

DESIGN FOR A CUSPIDOR.

SPECIFICATION forming part of Design No. 17,747, dated September 27, 1887.

Application filed February 1, 1887. Serial No. 226,193. Term of patent 7 years.

To all whom it may concern:

Be it known that I, WILLIAM T. MERSEREAU, of Orange, Essex county, New Jersey, have invented a new and original Design for a Cuspidor, of which the following is a specification.

My design is clearly shown in the accompanying drawings, wherein Figure 1 is a plan view, and Fig. 2 is a central transverse sectional view, of the same.

The nature of my design consists of a cuspidor case or cover having the outline and general formation of a crab. The center of my cuspidor has a circular opening formed therein,

provided with a step-like surface. The upper 15 part of this central portion has on one side an outer scalloped edge extending from end to end thereof.

Having described my invention, I claim—

The design for a cuspidor herein shown and described, consisting of the cuspidor of crab-like formation, having a central opening with a step-like surface.

WM. T. MERSEREAU.

In presence of—

WILLIAM V. H. HICKS,
A. SIDNEY DOANE.
